UNITED STATES PATENT OFFICE.

EDMUND H. WALKER, OF NEW YORK, N. Y.

FRICTION DRAFT GEAR.

Application filed August 7, 1924. Serial No. 730,667.

The invention relates to friction draft gear for railway cars.

The primary object of the invention, generally stated, is to provide a draft gear of the friction type in which means is provided to compensate for wear and consequently prolong the period of usefulness.

It is well known that in a friction draft gear the co-acting or contacting parts are subject to considerable wear which will, in the course of time, result in lost motion so that when an impact is applied, as when coupling cars, a hammer-like blow results which, not being properly cushioned, will cause crystallization of the metal and consequent breakage.

It is with the above facts in view that I have designed the present invention which has for a more particular object the provision of a draft gear of the friction type including a central and outer wedge blocks and embodying wear plates which are initially placed in position and which may subsequently be removed to permit the central wedge member engaged by the springs to move forwardly and take up any looseness between the areas of contact of the central wedge member with the outer wedge members and between the outer wedge members and the friction box.

A further object of the invention is to provide a friction draft gear not only embodying the above mentioned feature but further provided with means for reducing the length of the spring space within the barrel by a distance corresponding to the extent of forward movement of the central wedge member upon removal of the wear plates so that the length of the springs will be the same after removal of the wear plates as before.

To the attainment of the foregoing and other objects and advantages, the invention consists in the details of construction and arrangement to be hereinafter more fully described and claimed and illustrated in the accompanying drawings, it being, however, understood that the embodiment disclosed is merely a preferred exemplification, as many changes and modifications may be made provided that constitute no departure from the spirit of the invention or the scope of the claims hereunto appended.

In the drawings wherein like reference characters designate corresponding parts throughout the several views:—

Figure 1 is a plan view illustrating the

friction draft gear positioned in a railway draft rigging.

Figure 2 is a central vertical longitudinal section through the friction draft gear with the central wedge member in section and the outer wedge members in elevation.

Figure 3 is an end view from the left side of the draft gear shown in Figure 2.

Figure 4 is a view partly in longitudinal section at right angles to the plane in which Figure 2 is taken, the view being indicated by the line 4—4 on Figure 2.

Figure 5 is a view partly in longitudinal section similar to Figure 2 and showing the position of the parts subsequent to removal of the wear plates, this view also illustrating the take-up plate provided at the rear of the barrel.

Figure 6 is a cross section on the line 6—6 of Figure 5, looking toward the take-up plate or filler.

Referring to the drawings in detail, I have shown, in Figure 1, the invention applied to a friction draft gear positioned within a railway draft rigging involving the horizontal two-key Farlow construction in which the center sills 1 are provided with cheek plates 2 which, together with the sills, are suitably slotted for the accommodation of the keys in the usual manner. Located between the sills is a horizontal yoke 3 which has the forward ends of its arms slotted to receive the key 4 which connects the coupler 5 with the yoke, this key also extending through certain of the aligned slots in the sills and cheek plates. Another key 6 extends through a second series of slots in the sills and cheek plates and also through slots provided in the yoke arms and in a follower block 7 interposed between the butt of the coupler and the friction device. The numeral 8 designates a rear stop member or back stop located between the sills and with which the rear of the yoke contacts.

The draft gear or cushioning mechanism comprises a spring barrel or casing 9 which is engaged at its forward end within a friction box or head 10. This box is here represented as of rectangular form and is provided with inclined friction faces 11 with which cooperate the correspondingly inclined faces of outer friction members or wedge blocks 12 between which is arranged a central friction member or wedge block 13 which is movable through or within a central opening 14 in the head or box 10. The

larger, inner or rear, end of this central wedge member is formed with a flat face or seat 15 at the center of which is a rearward projection 16 extending through an opening 17 in a spring plate or follower 18 of a size to be capable of free movement longitudinally within the barrel and partly into the head or box 10. Within the barrel are outer and inner springs 19 and 20, respectively, which bear against the closed outer or rear end wall 21 of the barrel and which bear also against the spring plate 18.

The outer or inclined surfaces of the central wedge member 13 are formed with grooves 22 which receive ribs 23 on the contacting faces of the outer wedge members 12. The corners of the outer wedge members adjacent the center wedge member are preferably cut away, as indicated at 24, for the purpose of preventing incorrect assembling as it is obvious that the smooth outer surfaces of the outer wedge blocks are intended to engage the smooth inclined surfaces 11 of the friction box. The provision of the interfitting ribs and grooves is of vital importance inasmuch as they will insure proper movement of the parts when subjected to strain or impact, and danger of tipping or canting the wedge blocks will be prevented, while at the same time the proper frictional resistance is insured. Obviously, when pressure comes against the wedge blocks, the outer ones 12 will move toward each other and toward the closed end of the barrel while the central one 13 will move longitudinally into the barrel against the resistance of the springs 19 and 20. An excessive shock causes all the wedge blocks to move to such an extent that the follower 7 will engage the friction box 10 itself and transmit the strain through the barrel 9 to the rear stop 8.

In a structure of this character it is quite apparent that after prolonged use the friction at the contacting faces will cause wear which must be taken up to avoid lost motion, hammering and consequent crystallization. In view of this necessity, I form the central wedge block 13 with lateral extensions or lugs 25 extending within recesses 26 in the box or head 10, and within these recesses are located the shims or wear plates 27 against which the extensions or lugs 25 abut. When in the course of time the parts have worn to such an extent that an undesired looseness exists, it is intended that these shims or plates be removed or replaced with thinner plates so that the central wedge member 13 will be adapted to move forwardly a sufficient distance to compensate for the wear upon the friction producing surfaces. Such forward movement of the wedge 13 causes corresponding movements of the wedges 12 and restores the parts to effective operating position. The removal or replacement of the

shims or wear plates increases the distance within the barrel occupied by the springs and as this would be undesirable I make use of a filler or take-up plate 28 which is disposed within the closed end 21 of the barrel 70 and which may be held by a bolt 29 which passes through a counter-sunk hole 30 in the closed wall 21, through a suitable hole in the plate 28, and which is equipped with a nut 31. The thickness of the filler plate 28 75 is such as to compensate for the shims removed and may also take up the lost motion due to the set of the springs.

In the use of a draft gear constructed in accordance with this invention, it is possible, 80 by virtue of the removal or replacement of the shims or plates, to prolong the life of the mechanism to a great extent inasmuch as the lost motion, with the resultant destruction of the parts, will be eliminated. 85

Having now described my invention, what I claim is:—

1. In a friction draft gear, a friction box having inclined surfaces, a barrel engaged with the box, outer wedge blocks engaged within the box and having inclined surfaces contacting with the inclined surfaces thereof, a central wedge block located between and in engagement with the outer wedge blocks, a spring plate within the barrel 90 engaging the central wedge block, springs within the barrel engaging said spring plate, and removable means positioned between cooperating portions of the friction box and central wedge block and normally limiting outward movement of the central wedge block with respect to the friction box. 95

2. In a friction draft gear, a friction box having inclined surfaces, a barrel engaged with the box, outer wedge blocks engaged within the box and having inclined surfaces contacting with the inclined surfaces thereof, a central wedge block located between and in engagement with the outer wedge blocks, a spring plate within the barrel 100 engaging the central wedge block, springs within the barrel engaging said spring plate, and removable means normally limiting outward movement of the central wedge block 105 with respect to the friction box, said means including shims located within the friction box, and extensions on the central wedge block engaging said shims. 110

3. In a friction draft gear, a friction box having inclined surfaces, a barrel engaged with the box, outer wedge blocks engaged within the box and having inclined surfaces contacting with the inclined surfaces thereof, a central wedge block located between and in engagement with the outer wedge blocks, a spring plate within the barrel 120 engaging the central wedge block, springs within the barrel engaging said spring plate, and removable means normally 125

limiting outward movement of the central wedge block with respect to the friction box, said means including laterally extending lugs on the central wedge block, and 5 shims abuttingly engaged by said lugs, the friction box being recessed for the accommodation of said shims, said lugs and said spring plate.

4. In a friction draft gear, a friction box 10 having inclined surfaces, a barrel engaged with the box, outer wedge blocks engaged within the box and having inclined surfaces contacting with the inclined surfaces thereof of a central wedge block located between 15 and in engagement with the outer wedge blocks, a spring plate within the barrel engaging the central wedge block, springs within the barrel engaging said spring plate, and removable means normally limiting outward movement of the central wedge block 20 with respect to the friction box, and means insertable within the barrel in abutting engagement with the springs therein to compensate for the increase in distance between 25 the spring plate and the opposite end of the barrel caused by removal of said first named means.

5. In a friction draft gear, a friction box having inclined surfaces, outer wedge blocks 29 having inclined surfaces engaging said first

named inclined surfaces, a central wedge block interposed between said first named wedge blocks and formed with lateral extensions, said friction box having recesses 35 accommodating said extensions, shims removably mounted within said recesses and abuttingly engaged by said extensions, a spring plate engaged against said central wedge block, and a spring within the barrel 40 engaging said spring plate.

6. In a friction draft gear, a friction box having inclined surfaces, outer wedge blocks having inclined surfaces engaging said first named inclined surfaces, a central wedge block interposed between said first named 45 wedge blocks and formed with lateral extensions, said friction box having recesses accommodating said extensions, shims removably mounted within said recesses and abuttingly engaged by said extensions, a 50 spring plate engaged against said central wedge block, a spring within the barrel engaging said spring plate, and a filler plate adapted for insertion within the barrel in engagement with one end of the spring to 55 reduce the length of the spring space corresponding to the thickness of the shims.

In testimony whereof I affix my signature.

EDMUND H. WALKER.
